UNITED STATES PATENT OFFICE.

BARNEY MOORE, OF CHICAGO, ILLINOIS.

SHOE RACK.

1,405,539.

Specification of Letters Patent.

Patented Feb. 7, 1922.

Application filed October 29, 1920. Serial No. 420,378.

To all whom it may concern:

Be it known that I, BARNEY MOORE, a citizen of the United States, residing at Chicago, in the county of Cook and State 5 of Illinois, have invented new and useful Improvements in Shoe Racks, of which the following is a full, clear, and exact description.

My invention relates to means for suspending or hanging articles of apparel to walls or doors, and particularly to a shoe-rack. The object of my invention is to make 10 a rack that is, preferably, made of sheet metal, and is particularly adapted to be fastened to the inside of closet doors for the purpose of hanging shoes of all sizes and 15 styles and hold them rigid regardless of jarring or slamming of the door.

This I accomplish by means hereinafter 20 fully described and particularly pointed out in the claim.

In the drawings:

Figure 1 is a perspective view of a portion of a door showing my improvements 25 applied thereto.

Figure 2 is a front view of my improved rack.

Figure 3 is a vertical section taken on line 3, 3, Figure 2.

Referring to the drawings, A represents a door and B the mid-rail that separates the upper and lower panels of the same. My improved shoe-rack C consists of a strip of metal, that is of such shape as to provide a 30 lower portion c, provided at intervals with apertures for the passage of nails, screws or the like whereby the device may be secured in place for use, preferably as shown, and integral with the lower portion there 35 is an offset portion or rack d, the parts c and d being connected by an intermediate portion e, there being present two right angular bends, the portions being of such size that when the shoe rack is attached to 40 a support the heel engaging part will be maintained outstanding from the plane surface to which it is secured. It will be noted that the upstanding portion is of considerable height relative to the other portions 45 and that the part e that is integral with parts c and d is of such size that shoes when held by their heels will be maintained away from the support or door. The upper

edge of rack d is provided with a series of serrations f that have their upper angles 55 truncated and are of a depth and width exceeding the length and width of a heel of a shoe.

In order to hang a shoe in the rack, the heel of the same is placed in one of the serrations f so that the forward edges thereof 60 catch and hang wholly upon the converging edges of the serrations, with the foot of the shoe hanging downwardly. It makes no difference what the size of the shoe is or 65 what the width of its heel is in so far as the ability of my improvements to hang the same is concerned. A shoe having a narrow heel will engage the edges of the serrations f of the narrower lower portion thereof 70 while a shoe having a wider heel will engage the edges of said serrations at a point higher up, substantially as shown in Figure 2 of the drawings.

The rack will thus accommodate all sizes 75 of shoes, and provide a support for the same that will securely hold them and prevent their being easily displaced by the opening or closing of the door, while permitting their easy removal whenever desired. It 80 will be understood that my improved shoe-rack can be secured to walls or partitions of a building as well as to the doors thereof; the intention being to provide a shoe-rack that can be used anywhere. It will also be 85 apparent that the design of the rack as shown in the drawings, can be modified or changed without departing from the spirit of my invention. I prefer to truncate said serrations in order to prevent the upper 90 pointed angles of the same from scratching the surface of the shoes and from tearing adjacent clothing and also in order to reduce the vertical dimensions of the rack.

What I claim as new is:

As an improved article of manufacture a metallic shoe rack made up of a single piece of sheet metal having upper and lower portions of different widths, and an intermediate portion formed by right angular longitudinal bends which positions the upper and the lower portions in different planes, the aforesaid upper portion having V-shaped recesses which are spaced apart one from the other to provide between the recesses truncated portions, the portions being of such

dimensions that the inner faces of the recesses are adapted to engage opposite sides of the heel of a shoe so that the toe end of the shoe will depend and the sole will be
5 maintained away from the support to which the rack is attached.

In witness whereof I have hereunto set my hand this 24th day of October, 1920.

BARNEY MOORE.

Witnesses:

FRANK D. THOMASON,
VIOLET WARDELL.
